UNITED STATES PATENT OFFICE.

ST. CLAIR LAKE, OF POUGHKEEPSIE, NEW YORK, ASSIGNOR TO MOLINE PLOW COMPANY, A CORPORATION OF NEW YORK.

GRINDING-MACHINE.

1,396,130.

Specification of Letters Patent.

Patented Nov. 8, 1921.

Application filed March 8, 1919. Serial No. 281,394.

To all whom it may concern:

Be it known that I, ST. CLAIR LAKE, a citizen of the United States, residing at Poughkeepsie, in the county of Dutchess and State of New York, have invented certain new and useful Improvements in Grinding-Machines, of which the following is a specification, reference being had therein to the accompanying drawing.

10 This invention relates to machines for grinding blades or blanks, and is designed more particularly for grinding the cutting edges on the flat knife sections of the cutter bars of reapers, mowers and like machines, 15 and the invention consists of an improved and novel combination and arrangement of parts by which the blanks are presented in succession to an abrasive element or grinder which grinds them to a cutting edge, the 20 machine operating to handle the blanks automatically to perform the grinding operation in a speedy, uniform and effective manner.

In the machine embodying my invention, 25 the blanks are stored or held *en masse* in a blank holder or reservoir from which they are ejected into a blank carrier, which carrier advances and presents them in succession to and impinges their edges against the grinding face of an abrasive element, and while in this position, the carrier is reciprocated so as to move the edges of the blank to and fro across the grinding face, whereby 30 the blank is ground down on a bevel to a cutting edge, and finally the ground blank is discharged from the carrier.

In the more specific embodiment of the invention, the blank carrier is rotatably mounted and formed to hold a plurality of the 40 blanks which are ejected into it in succession from the holder, the carrier being turned or advanced on its axis intermittently to successively position the blanks for impingement against the abrasive element in the 45 form of a grindstone rotating about an axis at right angles to the axis of the carrier. The blank holder and blank carrier are sustained by a slide, which is movable to and from the grinder to engage and disengage 50 the blanks therewith in succession, the carrier being turned on its axis between the to and fro movements to position a new blank for grinding. The slide is carried by a carriage which is movable back and forth in a 55 path parallel with the face of the grinder,

so that with the edge of the blank engaged with the grinder, the reciprocating movements of the carriage will impart a like movement to the carrier, and the edge of the blank will be moved back and forth against the face of the grinder and the grinding operation effected.

In the accompanying drawings:

Fig. 1 is a top plan view of a grinding machine having my invention embodied therein.

Fig. 2 is a side elevation of the same with parts broken away to expose other parts to view.

Fig. 3 is a vertical sectional elevation on the line 3—3 of Fig. 1, as viewed in the direction of the arrows in said figure.

Fig. 4 is a vertical section on the line 4—4 of Fig. 1.

Fig. 5 is a fragmentary perspective view of the blank holder, blank carrier, and the grinder, showing the relations which said parts bear to each other.

Fig. 6 is a vertical sectional elevation on an enlarged scale on the line 6—6 of Fig. 3.

Fig. 7 is a similar view on the line 7—7 of Fig. 6.

Fig. 8 is a perspective view of one of the blanks before being subjected to the grinding operation.

Fig. 9 is a similar view of the same after it has had one of the cutting edges ground thereon.

Fig. 10 is a similar view showing both cutting edges ground.

The machine operates on a blank or plate A of the form shown in Fig. 8, and in the passage of the blank through the machine, one of its edges is ground on a bevel to form the cutting edge *a* as shown in Fig. 9. The blank is then placed in the machine in a different position, and on its second passage therethrough the other edge *a'* is ground, as shown in Fig. 10.

The machine comprises as its principal parts an abrasive element or grinder 1, a blank holder 2 in which the blanks A to be ground are stored, and a blank carrier 3 disposed between the holder and the grinder in position to receive the blanks from the holder and present them to the grinder.

The grinder in the present case is in the form of a rotary grindstone fixed to one end of a horizontal rotary shaft 4, mounted in bearings 5 on a slide 6 movable in guides on

a supporting frame 7, and driven by means of a pulley 4^a on the shaft, from any suitable source of power, the said slide being adjustable on the frame to compensate for wear of the stone, as will be more fully described later on.

The blank carrier 3 consists, in the present instance, of a six-sided body or drum 3^a, which is fixed to one end of a horizontal shaft 8 extending at right angles to and in a horizontal plane with the axis of the grindstone and parallel with the grinding face of the same, the said shaft being mounted in bearings in the upper ends of two standards 9 rising from a slide 10 movable to and from the grindstone, as shown more particularly in Figs. 2 and 3. The carrier is formed, as shown more particularly in Fig. 5, in each of its sides with two sockets or seats to receive and hold a pair of the blanks A, the said seats being each formed with an outer inclined shoulder 11 and an inner oppositely inclined shoulder 12, between which the blank fits, with its bottom edge bearing against the outer shoulder, and with one of its edges which is to be ground bearing against the inner shoulder, in which position of the blanks the other inclined edges to be ground will project beyond the seats in position to be presented to the grindstone. The blanks are confined between the shoulders by means of a cover plate 13 forming the outer walls of the sockets, which are open at one side to receive the blanks as they are ejected from the holder, as will be presently described. From the construction set forth, it will be noted that the blanks held on the carrier are supported in planes which are tangents to a circle described from the axis of the carrier as a center. Due to this fact, by turning the carrier intermittently on its axis, the blanks on the several sides may be presented in the proper inclination to the face of the grinder to cause the edges of the blanks to be ground down on the proper bevel to produce the cutting edges.

The blank holder 2 is in the form of a vertical receptacle or frame formed with two vertical internal channels in which the blanks are assembled one upon the other in two piles, as shown in Fig. 5, the said channels being of a contour which will hold the blanks in the same relative position they occupy in the seats or sockets in the carrier, so that they may be ejected from the holder in this position directly into the carrier. The holder is fixed at its lower end to a horizontal plate 14 sustained on a level with the upper side of the carrier, by standards 15 extending upwardly from the slide 10, and the bottom of the holder is open, so that the lowermost blanks of the piles will be in position to be engaged by an ejector blade 16, which is mounted to slide back and forth

beneath the holder in a guideway 17 formed on the upper side of the plate 14. When the ejector blade is in retracted position, the bottom blanks of the two piles will rest upon the bottom of the guideway 17, and as the ejector blade advances, it will engage the edges of the blank and push them forwardly from the holder and seat them in the sockets in the carrier, as shown in Fig. 5. In this ejecting action of a pair of blanks, the next pair above will be supported by the blade, and when the latter is retracted and reaches the position where it disengages the supported blanks, the latter will drop onto the bottom of the guideway in the position occupied by the previous blanks and in the path of the blade on its next advance.

The slide 10 is mounted in guideways 10^a in a carriage 18, which carriage is movable in guides 19 on a base frame 20, the said guides extending at right angles to the path of movement of the slide 10 and parallel to the face of the grindstone. As a result of the construction described, the blank carrier 3 may be moved to and from the grindstone to carry the edges of the blanks into and out of engagement with the stone, which movements are effected by the movement of the slide 10 on the carriage 18; and the blank carrier may be moved back and forth in the direction of its axis to reciprocate the blades while in engagement with the stone, these actions being effected by the movement of the carriage in its guides.

In the operation of the machine, the blanks are ejected from the blank holder in pairs into the seats in the carrier, and the carrier is advanced or turned on its axis to position the blanks at the proper angle to be engaged with the stone, this movement taking place while the slide 10 is in a retracted position. The slide is then moved toward the stone, thereby impinging the edges of the blanks against the stone. The carrier is now at rest, and while in this condition the carriage is reciprocated on its guides, thereby shifting the carrier axially and moving the edges of the blanks back and forth against the stone, which action, together with the rotation of the stone, will grind down the edges of the blanks on a bevel and produce cutting edges thereon, the ejection of the blanks from the holder into the carrier taking place during the reciprocating movements of the carrier. When the grinding operation is completed on a pair of the blanks, the slide 10 is retracted to give room for the turning of the carrier to bring the next pair of blanks into position, and the foregoing operations are repeated, the carrier being advanced to impinge the blanks and then reciprocated as before, and as the carrier continues in its rotation, the ground blanks gradually ap-

proach the position indicated by the letter X in Fig. 2, at which point they will fall from the carrier by gravity. These various movements of the parts occur automatically in timed relation to each other, the operating mechanism for the several parts, now to be described, receiving their motion from a driving shaft 21, and being coöordinated with each other in the timed relation stated.

10 The driving shaft 21 is mounted in bearings in the carriage 18, and is provided at one end with a driving pulley 22 which may be driven from any suitable source of power, and at its opposite end it has fixed to it a pinion 23 which imparts a slow rotation by means of a train 24 of reducing gears, to a crank disk 25, the crank pin 26 of which is pivotally connected by means of a link 27 with the base frame as at 28, as shown in Fig. 3. The driving shaft carries a bevel gear 29, see Fig. 1, which meshes with a bevel pinion 30 on one end of a countershaft 31, mounted in bearings 32 on the carriage 18, and the shaft 31 carries a worm 33 driving a worm wheel 34 on a transmitting shaft 35 mounted in bearings 36 on the carriage and extending at right angles to the countershaft. The transmitting shaft carries a cam drum 37 formed with a cam slot 38 engaging a roller 39 (see Fig. 2) on the outer end of a lever 40, which is pivoted between its ends as at 41 to the carriage 18, and is pivoted at its end as at 42 to the slide 10, whereby the slide, and consequently the blank carrier are moved to and from the grindstone. The cam slot 38 is of such form that in the to-and-fro movements imparted to the slide to correspondingly move the carrier, the movement toward the stone will be a rapid one until the blanks engage the same and the grinding operation begins, whereupon the further feed movement will be slower as the metal is removed from the edges of the blank, and when the operation is completed, the slide is quickly retracted to its former position.

15 The transmitting shaft 35 also carries a bevel gear 43 meshing with a bevel pinion 44 on the lower end of a shaft 45 mounted in bearings on the slide 10, the upper end of the shaft having fixed to it a bevel gear 46 (see Figs. 2 and 3) which engages a bevel pinion 47 on the end of a horizontal shaft 48 mounted in bearings in the standards 15 on the slide 10. The shaft 48 has a cam drum 49 fixed to it provided with a cam slot 49^a in which engages a pin 50 depending from the ejector blade, by which means the ejector blade is operated to eject the blanks 60 from the holder.

Beyond the worm 33 the countershaft 31 has fixed to it a sprocket wheel 51, around which passes a sprocket chain 52, which chain also passes around a larger sprocket wheel 53 mounted loosely on the shaft 8, which, it will be remembered, has the blank carrier fixed to it. By this means the sprocket wheel 53 is rotated continuously by the driving shaft through the medium of the countershaft, without, however, rotating the shaft 8 except intermittently, as will presently appear. The hub of the sprocket wheel carries a driving friction disk 54, see Fig. 4, which bears against a driven friction disk 55 pinned to the shaft 8, the driving disk being pressed yieldingly against the driven disk by means of a spiral spring 56 bearing at its inner ends against the sprocket wheel and bearing at its outer end against a nut 57 on the end of the shaft 8. The two coöperating friction disks constitute a clutch in the driving connections from the countershaft to the rotary blank carrier, the spring 56 being of a strength to cause the rotary motion of the driving disk to be imparted to the driven disk 75 and consequently to the blank carrier, except when the driven friction disk is restrained against rotation. As before stated, the blank carrier is turned on its axis only at intervals when it is in retracted position to permit the following blanks held in the carrier to be positioned relatively to the grindstone for the grinding operation, and this intermittent action is controlled automatically by the transmitting shaft, as shown more particularly in Figs. 1, 4, 6 and 7. Here it will be seen that the driven friction disk 55 is formed in its peripheral edge with a series of equally spaced notches 58, in any one of which is adapted to engage the upper end of a vertically movable rod 59 carrying a plunger disk 60 sliding in a cylinder 61 sustained by the slide 10 vertically beneath the disk 55, the plunger disk being acted on by an expansion spring 62 seated in the cylinder 80 and acting to thrust the rod yieldingly upwardly and maintain its upper end in engagement with the edge of the driven friction disk. The rod extends below the cylinder, and has fixed to its lower end a head 63 which stands in the path of a wiper finger 64 projecting radially from the end of the transmitting shaft 35. The upper end of the rod normally seats in one of the notches in the driven friction disk and holds said disk 90 against rotation, the driving friction disk at this time rotating continuously in contact with the driven disk. In the rotation of the transmitting shaft 35, the wiper finger thereon 95 engages the head 63 on the rod and quickly pulls the latter down against the force of the spring 62, thereby withdrawing the end of the rod from the notch in the driven friction disk and releasing the latter, the wiper immediately disengaging the head and permitting the rod to be instantly moved upwardly again by the spring with the upper end bearing against and riding on the upper end of the disk. The spring pressure of the rotat- 100

105 110 115 120 125 130

4
ing driving disk against the driven disk now causes the latter and the connected blank carrier to be turned, and this action will continue until the next notch in the disk arrives 5 opposite the upper end of the rod, whereupon the latter will seat in the notch and will bring the disk and consequently the blank carrier to rest. The edge of the driven disk is cammed, as shown, between the 10 notches to cause the rod to seat with certainty and to prevent overthrow of the disk.

By the mechanism described, the blank carrier is advanced on its axis step by step, which action is controlled automatically and 15 effected in timed relations to the back and forth movements of the carrier, to permit the latter to be turned to present the following blanks in position for the grinding operation.

20 In the operation of the machine, the blanks in the holder are ejected in pairs in succession into the carrier, the ejection of a pair of blanks taking place while the carrier is at rest, ~~as~~ far as motion on its axis is concerned, 25 but while it is being reciprocated axially and is moving the previously positioned blanks across the face of the grindstone. When the grinding operation of the engaged blanks is completed and produces one sharpened edge 30 on each of the blanks, the slide 10 moves back and retracts the carrier, whereupon the carrier makes a partial revolution to bring the next pair of blanks into grinding position, and then the carrier moves up toward 35 the stone and impinges the edges of these blanks against the same. The carriage 18 is now reciprocated and imparts a corresponding movement to the carrier in the direction of its axis, by which action the blanks 40 are moved back and forth against the stone, and when sufficiently ground, the carrier again retracts and is turned as before to bring a new pair of blanks into position, the driving mechanism for effecting these several 45 movements being coördinated with each other to produce them in the proper timed relations. After the machine has thus been operated to effect the grinding of one edge of each of the blanks in the holder, the discharged blanks are reinserted in the holder 50 but in reverse position, so that when ejected into the carrier, the unground edges will project therefrom in position to be presented to the stone.

55 In the accompanying drawings and foregoing description I have shown and described the blank holder formed to accommodate two piles of blanks, and the blank carrier formed to sustain on each of its six sides 60 a pair of blanks, but it will be understood that the invention is not limited to this particular form of the parts, as it is obvious that the blanks may be entered singly instead of in pairs into the carrier without departing from the limits of the invention.

The adjustment of the grindstone to compensate for wear is effected in the present instance, as shown in Fig. 2, by means of a hand wheel 65 on the end of a shaft 66 mounted in bearings on the frame 7 before 70 alluded to. The shaft 66 carries a worm 67 engaging a worm wheel 68 on a threaded feed shaft 69 mounted in bearings on the frame 7, and screwed through a lug 70 depending from the slide 6.

75 While in the foregoing description and accompanying drawings I have disclosed my invention embodied in the particular detail form and construction of the parts which I prefer to adopt and which in practice has 80 been found to answer to a satisfactory degree the ends to be attained, it will be understood that these details may be variously modified and changed by the skilled mechanic without departing from the limits of 85 the invention; and further it will be understood that the invention is not limited to any particular form or construction of the parts except in so far as such limitations are specified in the claims.

90 Having thus described my invention, its construction and mode of operation, what I claim and desire to secure by Letters Patent of the United States, is as follows:

1. In a grinding machine, the combination 95 of a grinder provided with a flat grinding face, a movable blank carrier provided with a plurality of blank seats adapted to hold the blanks with one edge exposed and extending parallel with the plane of the grinding face, and means for intermittently positioning the holder relatively to the grinder to present the blanks in succession in a plane inclined to the plane of the grinding face and with the edge of the blank impinged 100 against said face; whereby the impinged edge will be ground down on a bevel.

2. In a grinding machine, the combination 110 of a grinder, a blank carrier formed to hold a plurality of blanks, means for moving the carrier to and from the grinder to impinge the blanks against the same, and means coördinated with the to and fro movements of the carrier for advancing the carrier between its to-and-fro movements to bring the 115 successive blanks into position for grinding.

3. In a grinding machine, the combination 120 of a grinder, a blank carrier formed to hold a plurality of blanks, means for advancing the carrier intermittently to position the successive blanks for presentation to the grinder, and means coördinated with the intermittent advance of the carrier for moving the carrier to and from the grinder to impinge the blanks thereagainst.

125 4. In a grinding machine, the combination 130 of a grinder, a rotary blank carrier formed to hold a plurality of blanks, means for moving the carrier bodily to and from the grinder to impinge the blanks thereagainst,

and means coördinated with the bodily movements of the carrier for advancing the carrier on its axis of rotation to position the successive blanks for impingement against the grinder.

5. In a grinding machine, the combination of a grinder provided with a flat grinding face, a movable blank carrier provided with a plurality of blank seats adapted to hold the blanks with one edge exposed and extending parallel with the plane of the grinding face, means for intermittently positioning the carrier relatively to the grinder to hold the successive blanks in a plane inclined to the plane of the grinding face, and means for moving the carrier to and from the grinder to impinge the edge of the successive blanks thereagainst.

6. In a grinding machine, the combination of a grinder, a carriage for receiving and holding blanks to be ground, means for automatically feeding blanks to the carriage, means for moving the carriage to and from the grinder to impinge the blanks against the same, means for moving the carriage back and forth to move the blanks on the grinder during the grinding operation, and means coördinated with the to and fro movement of the carriage for moving the carriage to bring successive blanks into position for contact with the grinder and to bring the carriage in position to receive additional blanks.

7. In a grinding machine, the combination of a grinder, a blank carrier formed to hold a plurality of blanks, means for moving the carrier to and from the grinder to impinge the blanks against the same, means coördinated with the said to and fro movements for advancing the carrier between its to and fro movements to position the blanks in succession for impingement against the grinder, and means for reciprocating the carrier between its advancing movements to move the blanks back and forth against the grinder.

8. In a grinding machine, the combination of a grinder, a blank holder formed to hold the blanks *en masse*, a blank carrier in position to receive the blanks from the holder and formed to hold a plurality of blanks at one time for successive impingement against the grinder, means for moving the carrier periodically to position the held blanks in succession for impingement against the grinder, the said carrier being brought to rest between each periodic movement, an ejector in position to engage the blanks in the holder and operable to eject the same into the carrier, and means for operating the ejector at intervals corresponding to the rest periods of the carrier.

9. In a grinding machine, the combination of a grinder, a blank holder formed to hold the blanks *en masse*, a blank carrier in position to receive the blanks from the holder

and formed to hold a plurality of blanks for successive impingement against the grinder, means for advancing the grinder periodically to position the held blanks for impingement against the grinder, means for moving the carrier to and from the grinder to impinge the positioned blanks thereagainst, means for reciprocating the carrier between its periodic advances while the blanks are in contact with the grinder, an ejector in position to engage the blanks in the holder and operable to eject the same into the carrier, and means for operating said ejector at intervals between the periodic advances of the carrier.

10. In a grinding machine, the combination of a grinder, a blank holder formed to hold a pile of superposed blanks, a rotary blank carrier in position to receive the blanks from the holder and position them in operative relation to the grinder, an ejector in position to engage the blanks in the holder and operable to eject the same in succession into the carrier, means for rotating the carrier at intervals to position the blanks successively in operative relation to the grinder, means for moving the carrier to and from the grinder to impinge the blanks in succession thereagainst, means for reciprocating the carrier between its intervals of rotation while the blanks are in contact with the grinder, and means for operating the ejector during such reciprocating movements of the carrier.

11. In a grinding machine, the combination of a grinder, a rotary blank carrier provided with a plurality of seats adapted to support blanks with their edges in position for impingement against the grinder, means for rotating the carrier at intervals to position the blanks relatively to the grinder, and means for moving the carrier to and from the grinder to impinge the edges of the blanks against the same, and to permit the carrier to be turned to bring a new blank into position.

12. In a grinding machine, the combination of a grinder, a rotary blank carrier provided with a plurality of seats adapted to support the blanks with their edges arranged against the grinder, means for moving the carrier toward the grinder to engage the edge of the blank therewith, means for moving the carrier away from the grinder to disengage the blank therefrom, and means coördinated with said movements for turning the carrier while the blank is disengaged to bring a new blank into position.

13. In a grinding machine, the combination of a grinder, a base frame, a slide movable on the base frame to and from the grinder, a rotary blank carrier sustained by the slide and formed to hold the blanks with their edges in position to be impinged against the grinder, means for advancing

and retracting the slide to and from the grinder to respectively impinge the blank thereagainst and disengage it therefrom, and means for rotating the carrier to position a new blank when the slide is retracted.

14. In a grinding machine, the combination of a grinder, a base frame, a carriage movable on said base frame, a slide movable on the carriage at right angles to the path of movement of the carriage, a blank carrier sustained by the slide and formed to hold a blank with its edge in position for impingement against the grinder, means for advancing the slide to and from the grinder to engage the blank therewith and disengage it therefrom, means for reciprocating the carriage while the blank is engaged with the grinder, and means for moving the carrier to position a new blank while the slide is in retracted position.

15. In a grinding machine, the combination of a grinder, a base frame, a carriage mounted thereon parallel with the plane of the face of the grinder, a slide movable on the carriage to and from the grinder, a rotary blank carrier on the slide formed to hold the blanks with their edges in position to be impinged against the grinder, means for advancing and retracting the slide to and from the grinder to engage the blanks therewith and disengage the same therefrom, means for reciprocating the carriage while the blanks are engaged with the grinder, and means for rotating the carrier to bring a new blank into position when the slide is retracted.

16. In a grinding machine, the combination of a rotary grinder, a blank carrier formed to hold the blanks with their edges in position to be impinged against the grinder, and movable to and from the same, and operating means for the carrier acting to feed the same rapidly toward the grinder to effect the initial engagement of the blank therewith, and operating thereafter to feed the carrier more slowly during the grinding operation.

17. In a grinding machine, the combination of a grinder provided with a grinding face, a blank carrier rotatable about an axis extending parallel or substantially so with said grinding face, and provided with a plurality of seats for the blanks at intervals around the carrier, and formed to sustain the blanks with their edges in position to be engaged with the grinder in succession, means for rotating the carrier on its axis to position the blank in a plane inclined to the plane of the face of the grinder, and means for moving the carrier toward the grinder to cause the edge of the blank to impinge thereagainst at such inclination.

18. In a grinding machine, the combination of a rotary grinder provided with a grinding face, a blank carrier rotatable about

an axis extending parallel or substantially so with the face of the grinder, means for supporting a blank on the carrier in a plane tangent to a circle described from the axis of the carrier as a center, and means for advancing the carrier on its axis to position the blank in a plane inclined to the plane of the face of the grinder.

19. In a machine for grinding a cutting edge on blanks, a carrier for the blanks rotatable about an axis, and provided with means to sustain the blanks in planes tangential to a circle described from the axis of the carrier as a center, with the edges of said blanks in position to be engaged with the grinder.

20. In a grinding machine, the combination of a grinder provided with a grinding face, a carrier for the blanks rotatable about an axis parallel or substantially so with the face of the grinder, means on said carrier to sustain the blanks at intervals therearound in planes tangent to a circle described from the axis of the carrier as a center, with their edges in position to be engaged with the grinder, and means for rotating the carrier to position the blanks in succession in a plane inclined to the plane of the face of the grinder.

21. In a grinding machine, the combination of a grinder provided with a grinding face, a carrier for the blanks rotatable about an axis parallel or substantially so with the face of the grinder, said carrier having means for sustaining the blanks at intervals therearound in planes tangent to a circle described from the axis of the carrier as a center, means for moving the carrier to and from the grinder to respectively engage and disengage the edges of the blanks therewith, and means for advancing the carrier on its axis when it is moved away from the grinder, to position the blanks in succession in a plane inclined to that of the face of the grinder.

22. In a grinding machine, the combination of a grinder provided with a grinding face, a base frame, a carriage movable on the base frame in a path parallel or substantially so with the face of the grinder, a drive shaft, means operated thereby for reciprocating the carriage on the base frame, a slide movable on the carriage to and from the grinder, a shaft on the carriage operated by the drive shaft, connections between such shaft and slide for reciprocating the same, a rotary carrier for the blanks mounted on the slide, and driving connections between said drive shaft and the carrier for rotating the latter.

23. In a grinding machine, the combination of a grinder provided with a grinding face, a base frame, a carriage movable on the base frame in a path parallel or substantially so with the face of the grinder, a drive shaft, means operated by the drive shaft for reciprocating the carriage on the base frame,

a slide movable on the carriage to and from the grinder, a countershaft on the carriage rotatable by the drive shaft, a transmitting shaft on the carriage rotatable from the 5 countershaft, driving connections between the transmitting shaft and slide for reciprocating the latter, a blank carrier mounted for rotation on the slide, and driving connections between the countershaft and blank 10 carrier for rotating the same.

24. In a grinding machine, the combination of a grinder provided with a grinding face, a base frame, a carriage movable on the base frame in a path parallel or substantially 15 so with the face of the grinder, a drive shaft, means operated by the drive shaft for reciprocating the carriage on the base frame, a slide movable on the carriage to and from the grinder, a shaft on the 20 carriage operated by the drive shaft, connections between said shaft and slide for reciprocating the latter, a rotary carrier for the blanks, connections between the drive shaft and carrier for rotating the same, a 25 holder for the blanks sustained by the slide, an ejector also sustained by the slide and operable to engage the blanks and eject the same into the carrier, and connections 30 between the slide operating shaft and ejector for operating the latter.

25. In a grinding machine, the combination of a grinder provided with a grinding face, a base frame, a carriage movable on the base frame parallel or substantially 35 so with the face of the grinder, a drive shaft, means operated thereby for reciprocating the carriage, a slide movable on the carriage to and from the grinder, a countershaft on the carriage operated by the drive shaft, a 40 transmitting shaft on the carriage operated by the countershaft, connections between the transmitting shaft and slide for recipro-

cating the same, a blank carrier rotatable on the slide, driving connections between the carrier and countershaft for rotating the 45 carrier, a holder for the blanks mounted on the slide, an ejector also mounted on the slide and operable to eject the blanks from the holder into the carrier, and connections between the transmitting shaft and ejector 50 for operating the same.

26. In a grinding machine, the combination of a grinder, a blank carrier movable intermittently to position the blank for impingement against the grinder, and movable 55 also to and from the grinder to impinge the blank thereagainst, a driving shaft, operating connections between the driving shaft and carrier including a clutch, means operated by the driving shaft for controlling the 60 clutch to move the carrier intermittently, and means operated by the driving shaft for effecting the to and fro movements of the carrier.

27. In a grinding machine, the combination of a grinder, a rotary blank carrier movable intermittently on its axis to position the blanks for impingement against the grinder, and movable also bodily to and from the grinder to impinge the blanks 70 thereagainst, a driving shaft, a counter-shaft operated by the driving shaft, operating connections between the countershaft and carrier for rotating the latter, said connections including a clutch, a transmitting 75 shaft operated by the counter shaft and acting to move the carrier to and from the grinder, and means operated by the transmitting shaft for controlling the clutch to rotate the carrier intermittently.

In testimony whereof, I have affixed my signature hereto.

ST. CLAIR LAKE.
